UNITED STATES PATENT OFFICE.

LOUIS GAETAN AGOSTINI, OF PARIS, FRANCE.

HAIR CURLER.

Application filed February 17, 1922. Serial No. 537,296.

To all whom it may concern:

Be it known that I, LOUIS GAETAN AGOSTINI, a citizen of the Republic of France, residing at 1 Rue Davy, Paris, France, have invented certain new and useful Improvements in Hair Curlers, of which the following is a specification.

This invention relates to improvements in hair curlers of the type used for permanently waving ladies' hair.

Hair curlers of this type usually consist of a slotted end piece and a tube connected together by a spring controlled ratchet device enclosed within the latter. These curlers are used in the following manner. A lock of hair is taken and tied together near the scalp with a piece of string. The string is fixed in the slot of the end piece and the hair is wound on the tube, the end of the hair being fastened with another piece of string. The end piece is then held with pliers and the tube is turned so as to tighten the coils on the curler; after which the hair is moistened with a solution of borax and enclosed in a paper capsule which is placed in an electrical heater.

The principal disadvantages of such curlers are, first, that the hair may be damaged because of the necessity of holding the end piece with pliers when tightening the coils upon the curler; second, that it is difficult to remove the curler without damaging the hair; and third, that it is impossible to clean the enclosed parts of the curler, which parts are very liable to corrosion because of the use of borax.

According to this invention I employ a curler in which the end piece is secured to a central rod passing right through the tube and fitted with a milled knob which is pressed by a spring against the other end of the tube so as to prevent rotation, either by the friction between the two parts, or preferably by the definite engagement of teeth provided on the two parts. In this way the coils of hair may be tightened after they have been wound upon the curler by merely catching hold of the milled knob, pulling it out of engagement with the tube, and turning the one relatively to the other. After treatment the hair can be loosened by pulling out the milled knob and turning in the opposite direction, but I prefer to facilitate the undoing of the hair by slightly tapering the whole curler, and by employing a vertical slot in the end piece instead of the

usual hook, which is liable to catch in the hair. I prefer also to screw the end piece to the central rod, and to extend the latter at the other end so that it passes right through and projects beyond the milled knob. The former enables the device to be taken to pieces for cleaning, and the latter enables the end piece and the tube to be slightly separated for the purpose of oiling by merely pressing in the projection.

In the annexed drawings which illustrate a curler made in accordance with this invention, and throughout which the same reference figures denote the same parts:—

Figure 1 is a view of the complete curler,

Figure 2 is a section of the tube of the curler,

Figure 3 is an end view of Figure 2,

Figure 4 is a view of the central rod and milled knob,

Figure 5 is a view of the end piece partly in section,

Figure 6 is a section of Figure 4,

Figure 7 is a view of the central rod,

Fig. 8 is a view showing the curler in use.

In these figures 1 is the tube provided with teeth 2 at one end which fits into the annular groove 3 in the milled knob 4. 5 is the central rod having at one end the thread 6 screwing into the hole 7 in the end piece 8, which is provided with a longitudinal slot 9. At the other end of the central rod 5 are provided a hole 10, a longitudinal slot 13 and an extension 12 of reduced diameter. One end of the spring 11 passes through the hole 10, and the other end presses against the inside of the bent over edge of the cylindrical extension 15 of the milled knob 4. The pin 14 passes through the slot 13 and fits tightly into the milled knob 4, so that the latter can slide but cannot turn upon the rod 5. The extension 12 of the rod 5 passes through a hole in, and projects beyond, the milled knob 4.

It will be seen that the spring 11 causes the tube 1 to be gripped between the end piece 8 and the milled knob 4, and that the pin 14 of the latter is thus pressed into the teeth 2 of the former so that the two are locked together and have to be pulled out of engagement in order to be turned. The relative turning of the milled knob 4 and the tube 1 after they have been pulled out of engagement causes the relative turning of the end piece 8 and the tube 1, and thus permits of the tightening or loosening of the

coils of hair wound thereon, while the tapering of the tube 1 and the provision of the slot 9 allow the curler to be pulled out of the coils without risk of catching in and 5 damaging the hair. It will also be seen that by unscrewing the end piece 8 from the rod 5 the latter may be taken out of the tube 1 and cleaned, while by pressing the 10 projection 12 the end piece 8 will be pushed away from the tube 1 so that the end of the rod 5 may be oiled without being dismantled.

Having now particularly described and 15 ascertained the nature of my said invention and in what manner the same is to be performed I declare that what I claim is:—

1. A hair curler, comprising a tube, a central rod inserted through the bore of the tube and projecting therebeyond at opposite 20 ends; an end piece on one end of the rod; a knob on the other end of said rod; and a spring acting to normally grip the knob to the adjacent tube end and thereby prevent relative rotation between the rod and 25 tube.

2. A hair curler, comprising a tube having a toothed end; a central rod inserted through the bore of the tube and projecting therebeyond at opposite ends; a knob on the end 30 of the rod adjacent the toothed end of the tube and having teeth for engagement with the tube teeth to prevent relative rotation between the tube and rod; a spring within said knob acting to normally maintain the 35 two sets of teeth engaged; and an end piece on the other end of the rod.

3. A hair curler, comprising a tube; a central rod inserted through the bore of the tube and projecting therebeyond at opposite 40 ends; a knob mounted to slide on one end of the rod but held against rotation on said end; a spring within the knob acting to normally couple the latter and the adjacent tube end to prevent relative rotation between the rod and tube until such coupling is terminated by the sliding movement of the knob on said 45 rod; and an end piece on the other end of the rod.

4. A hair curler, comprising a tube; a

central rod inserted through the bore of the tube and projecting therebeyond at opposite ends, said rod having at one end a longitudinal slot; a knob slidably mounted on the slotted end of the rod and having a central opening through which the terminal of the rod extends; a cross-pin carried by said knob and extending through said slot to limit the sliding movement of the knob on, and to prevent its rotation relative to, the rod; a spring within the knob acting to normally couple the latter and the adjacent tube end together to prevent relative rotation between the rod and tube until such coupling is terminated by the sliding movement of the knob; and an end piece on the other 65 end of the rod.

5. A hair curler, comprising a tapered tube, a central rod inserted through the bore of the tube and projecting beyond the same at opposite ends; a knob mounted on the 70 end of the rod adjacent the larger end of the tube and adapted to slide on said rod end but held against rotation thereon; a spring normally coupling said knob to said tube end to prevent relative rotation between the rod and tube until such coupling is terminated by the sliding movement of the knob; and a removable end piece on the other end of the rod.

6. A hair curler, comprising a tube; a central rod inserted through the bore of the tube and projecting therebeyond at opposite ends; a knob on one end of the rod; means associated with the knob for normally preventing relative rotation between the rod and tube; and an end piece on the other end of the rod.

7. A hair curler, comprising a tapered tube; a central rod inserted through the bore of the tube and projecting therebeyond at 90 opposite ends; a knob on one end of the rod; means associated with the knob for normally preventing relative rotation between the rod and tube; and an end piece removably threaded on the other end of the rod.

In testimony whereof I affixed my signature.

LOUIS GAETAN AGOSTINI.
